UNITED STATES PATENT OFFICE.

EMIL HAEFELY, OF BASEL, SWITZERLAND.

WINDING MACHINE FOR THE MANUFACTURE OF INSULATING TUBES, HOLLOW
INSULATING CYLINDERS, AND THE LIKE.

Application filed October 25, 1919. Serial No. 333,343.

To all whom it may concern:

Be it known that I, EMIL HAEFELY, a citizen of the Swiss Republic, and resident of Basel, Switzerland, have invented new and useful Improvements in Winding Machines for the Manufacture of Insulating Tubes, Hollow Insulating Cylinders, and the like, of which the following is a full, clear, and exact specification.

10 The invention relates to a winding machine for the manufacture of insulating tubes, hollow insulating cylinders and the like in electro-technology from a band of fibrous material which after treatment with 15 an agglutinant is wound on to a winding mandrel between heating cylinders under pressure.

In a machine of this type, since the diameter of the formed tube or cylinder varies 20 during the process of winding the fibrous material from which it is constructed, it is necessary that the direction of pressure at the contact points of the wound material with the heating cylinders should remain 25 constant in order that the band of fibrous material between the heating cylinders for smaller or larger diameters of the wound product may subtend the same angle and thereby effect an evenly stretched and 30 smooth winding of the band of fibrous material.

According to the present invention this is achieved by causing the freely rotatable heating cylinders during the process of winding to be gradually moved apart from 35 one another by means of an adjusting device, so that the angle between the directions of pressure at the contact points of the winding material with the heating cylinders remains 40 constantly approximately the same. The radial components of the pressure at the said contact points will thus experience no appreciable alteration and consequently by reason of this even pressure the wound 45 product from the commencement to the conclusion of the winding process is perfectly homogeneous.

In machines of considerable width, in 50 which the heating cylinders are relatively long and of relatively small diameter, and are provided with supporting shafts for the prevention of bending, these supporting shafts are preferably located in common bearing slides with the heating cylinders

in such a manner that the supporting shafts 55 take part in the outward movement of the heating cylinders away from one another.

The accompanying drawings illustrate a 60 constructional form of machine embodying the invention.

Fig. 1 is a view in end elevation of the machine adapted for the formation of insulating tubes on a winding mandrel.

Fig. 2 is a similar view of the same machine when a larger mandrel is employed 65 as the winding former.

Fig. 3 is a plan view from above of the machine shown in Fig. 1.

Fig. 4 is a vertical section on the line 70 A—B of Fig. 1.

The two heating cylinders *a*, *b* are mounted so as to be freely rotatable in sliding bearings *c* carried by the side portions *s* of the frame of the machine. Their displacement is effected by means of two rotatable 75 screw-threaded spindles *d* having right and left threads, so that by rotating the spindles *d* the heating cylinders *a*, *b* can be moved towards or away from one another. For the purpose of rotating the spindles *d* 80 a bevel gearing *e* and a handle *f* are provided. Alternatively the rotation of the screw-threaded spindles can be arranged to be effected by means of an automatic feed device, dependent for example upon the operation of the winding action. 85

The band of fibrous material, for instance a band of paper *g*, which is coated or impregnated with an agglutinant, is drawn in 90 on to a rotatable winding mandrel *h*, freely supported, above and between the heating cylinders *a*, *b*. The mandrel *h* is driven from any desired source of power by means of a flexible coupling or a universal joint for example, allowing of vertical displacement 95 of the mandrel within the limits of variation of the diameter of the paper roll. Vertically above the mandrel *h* and midway between the vertical planes passing through the axes of the heating cylinders is a small pressure cylinder *i* and a heavy pressure roller *k*. 100

The weight of the roller *k* transmitted through the pressure cylinder *i* causes each 105 layer of the band *g* to be pressed against the next layer underneath, so that owing to the fact that under the heating action of the cylinders *a*, *b* the agglutinant becomes lique-

fied, the successive layers of the band of fibrous material are pressed together closely and compactly together in a known manner in order to form a firm tubular structure. The component pressures at the contact points of the winding material with the heating cylinders *a*, *b* are so adjusted that their directions of pressure are inclined to each other at an angle of 90°, and both pass 10 through the axis of the winding mandrel. This angle, due to the possibility of moving the two heating cylinders apart, can be maintained constant at all stages of the winding process, as will be seen from a comparison 15 of Figs. 1 and 2, in spite of the fact that as the diameter of the wound product increases the axis of the winding mandrel is raised. The radial components of the pressures at the contact points of the winding material 20 with the heating cylinders therefore remain constant in magnitude and direction, so that the drawing-in of the band of fibrous material between the heating cylinders for smaller or larger diameters of the wound 25 product is effected over the same angle formed by the component pressure directions. Hence with a constant effective pressure a perfectly smooth and evenly tensioned application of the band of fibrous material is effected as is necessary for insulating 30 purposes of an electro-technical nature.

According to the drawing, the heating cylinders *a*, *b* with small diameter are comparatively long (see Fig. 3) and are liable 35 to bend under the considerable pressure to which they are subjected unless special precautions are taken. In order to prevent such bending of the heating cylinders, two supporting shafts *m*, *n*, of larger diameter 40 in the middle than at either end, are provided which support the heating cylinders *a*, *b* at a middle point. These supporting shafts *m*, *n* are supported in the same sliding bearings *c* as the respective heating 45 cylinders *a*, *b* (see Fig. 4) so that they partake of the outward movement of the heating cylinders.

It will be understood that the initial position of the heating cylinders *a*, *b* is determined in accordance with the size of the winding mandrel to be employed. In Fig. 1 the heating cylinders for use with a winding mandrel of small diameter are first set very close together; in Fig. 2 they are shown as 55 set to a greater distance apart for use with a larger size of winding mandrel. The movement apart of the heating cylinders however from their initial position must

always correspond with the progress of the winding process.

What I claim is:

1. A winding machine for the manufacture of insulating tubes, insulating hollow cylinders and the like for electrotechnical purposes from a band of fibrous material supplied with an agglutinant, comprising two freely rotatable and horizontally adjustable heating cylinders, bearing slides for supporting and guiding the same in horizontal direction, a freely supported driven rotary winding mandrel between the said heating cylinders capable of free elevation to wind the band upon it and to frictionally rotate said heating cylinders, a freely rotating heavy pressure cylinder, a freely rotating smaller intermediate pressure cylinder arranged to transmit the pressure of said heavy cylinder onto the winding mandrel, and positively acting common adjusting means connected with said bearing slides to move gradually and simultaneously the heating cylinders apart from each other during the winding operation, substantially as and for the purpose described.

2. A winding machine for the manufacture of insulating tubes, insulating hollow cylinders and the like for electro-technical purposes from a band of fibrous material supplied with an agglutinant, comprising two freely rotatable and horizontally adjustable heating cylinders of relatively small diameter, bearing slides for supporting and guiding the same in horizontal direction, a freely supported driven rotary winding mandrel between the said heating cylinders to wind the band upon it and to frictionally rotate said heating cylinders, a freely rotatable pressure cylinder arranged to exert thereon the necessary pressure for the winding operation and to be frictionally rotated by the winding mandrel, shafts arranged below the heating cylinders to support the same and to thus prevent their bending, and positively acting common adjusting means connected with said bearing slides for gradually and simultaneously moving apart the heating cylinders from each other during the winding operation, substantially as and for the purpose described.

In witness whereof I have hereunto signed my name this 30th day of September, 1919, in the presence of two subscribing witnesses.

EMIL HAEFELY.

Witnesses:

H. H. DICK,
AMAND BRAUN.
